[57] CLAIM

The ornamental design for a pin straightening and prying tool or the like, substantially as shown and described.

DESCRIPTION

FIG. 1 is a left side elevational view of pin straightening and prying tool or the like embodying my new design;
FIG. 2 is a top plan view thereof;
FIG. 3 is a bottom view thereof;
FIG. 4 is a right side elevational view thereof;
FIG. 5 is a frontal end view thereof; and
FIG. 6 is a rear end view thereof.
